UNITED STATES PATENT OFFICE.

JAMES F. TRAVIS, OF NEW YORK, N. Y.

DESIGN FOR A GASALIER.

Specification forming part of Design No. 6,808, dated August 19, 1873; application filed August 4, 1873.

A.

To all whom it may concern:

Be it known that I, JAMES F. TRAVIS, of the city of New York, in the county and State of New York, have invented a new and original Design for a Gasalier, which will be fully understood from the following description in connection with the accompanying drawing.

My present design is more particularly intended for that style of gasalier which is hung from a gas-opening in the ceiling, and hence visible on all sides.

A designates the stem, B the body containing the distributor, and C C the branches or arms of a gasalier, all of which parts are constructed so as to perform the ordinary mechanical duties. D is a pendant which, in connection with the branches C C and stem A, gives to the device somewhat the appearance of a cross. These parts may be round or square in cross-section, or ribbed, as desired, and I preferably, though not necessarily, apply some contrasting color along the surface, lettered a a, and the same may be done as to the stem and pendant, if desired. The body B is provided on one or both sides with a medallion, M, representing a head or other suitable figure. To the lower sides of both branches C C, and to the pendant D, the castings or strips E F G are attached by connecting-bars b c d, in such manner that a space intervenes between the strips E F G and the parts C D. It will be noticed that the strips E E run parallel to the arms C, and the strips G G parallel to the pendant D, while the strips F connecting them are curved to correspond,

in a measure, with the shape or outline of the body B. I preferably provide the strips E G with ornamental outer ends e f, and the strips F with knobs or projecting pieces g. To the upper side of the branches C C, and to the stem A, on both sides of said stem, there are attached castings or strips H I J, by bars h i j, leaving an intervening space, as in the case just above described. The strips H H being parallel with the branches C C, and the strips J J running parallel with the stem A and the strips I I, connecting them, being curved similarly to the strips F F, just described, and the outer ends of these strips H J are preferably provided with knobs or ornaments k l. The branches C C are shown as provided with cocks or plugs having ornamental thumb-pieces or keys m m for turning them, and also with globe-rings n, and the stem is also shown as provided with appropriate relieving-collars p p.

My present invention furnishes a very neat, ornamental, and attractive design for a pendant or hanging gasalier.

What I claim as my invention is—

A design for a gasalier in which the body is ornamented with a medallion on one or both sides, and the stem, pendant, and branches are provided with the ornamental strips E F G and H I J, substantially in the manner herein shown and described.

JAMES F. TRAVIS.
